[57] CLAIM

The ornamental design for a combined barbecue grill and ring shelf, as shown and described.

DESCRIPTION

FIG. 1 is an isometric view of a combined barbecue grill and ring shelf showing our new design;

FIG. 2 is a plan top view thereof;

FIG. 3 is a front elevational view thereof;

FIG. 4 is a rear elevational view thereof;

FIG. 5 is a bottom plan view thereof;

FIG. 6 is a right side view thereof;

FIG. 7 is a left side view thereof; and,

FIG. 8 is a right side elevational view thereof with the grill lid in an open position;

The structure shown in broken lines in FIGS. 1-8 is shown for illustrative purposes only and forms no part of the claimed design.
